SEMI-AUTOMATIC TELEPHONE SYSTEM.

1,323,265.

Specification of Letters Patent.

Patented Dec. 2, 1919.

Application filed March 19, 1914, Serial No. 825,937. Renewed October 18, 1919. Serial No. 331,747.

To all whom it may concern:

Be it known that we, GEORG GRABE, a citizen of the German Empire, FRITZ LUBBERGER, a citizen of the German Empire, 5 GEORG FRÜBING, a citizen of the German Empire, and HENDRICH BERTUS RÜTTER, a citizen of the Kingdom of Holland, and respectively residing at Nikolas See, near Berlin, Germany, Halensee, near Berlin, 10 Germany, Charlottenburg, near Berlin, Germany, and Amsterdam, Netherlands, have invented certain new and useful Improvements in Semi-Automatic Telephone Systems, of which the following is a specification.

This invention relates to apparatus for supervising the exchange positions in semi-automatic telephone systems.

In semi-automatic telephone systems, *i. e.* 20 in systems in which operators are employed for receiving the calls and adjusting the selectors, it is very important to supervise the single exchange position in order to assure proper reception of the calls and proper 25 operation of the keys or the like provided at the positions. The supervision of the exchange positions by special supervision officials, as is possible in manual operation, cannot in this case produce the desired result, because the adjustment of the keys at the exchange positions takes place very rapidly and after the adjustment of the 30 selectors the keys are at once adjusted afresh. In addition it is preferable to perform the supervision secretly in order that the time when the control is exercised may not be noticed at the position under observation. The listening control well known in manually operated central stations does 35 not in itself suffice for semi-automatic working as the succession of impulses takes place too rapidly.

An important object of our invention is 40 to provide separate from the exchange positions an observation station which admits of the possibility of listening to the desired number informed by a calling telephone station to an observing exchange position, and at the same time the testing of the subsequent adjustment for communicating the 45 current impulses which is effected by the

exchange position under observation. To this end, suitable means are provided at the observation position for rendering visible the adjustment of the key board of the exchange position at the observation position or recording the current impulses emitted at the exchange position.

The constant recording of a selector adjustment, which is once brought about, is of great importance for semi-automatic operation, because it admits of subsequent testing of the adjustment of the keys affected by an operator, and also affords a valuable and reliable record of the supervising official with regard to the operator which can be rendered still more valuable by recording by suitable means *e. g.* a Poulsen apparatus, also the talk between the operator and the calling subscriber. In automatic 71 working this arrangement is also important because it enables any complaints of a subscriber to be tested as to their justification.

A further object of our invention is to provide means by which the apparatus, *e. g.* preselectors, serial selectors, group selectors, connectors, number senders and the like, which are worked with the working stations, are brought under the influence of the place of observation by the official at the place holding or locking the said apparatus by suitable manipulations in the normal connection of the system when he perceives or suspects errors, in order to be able to make the requisite determinations with greater certainty and in order to detect a defective apparatus or an operator who is not paying sufficient attention. To this end, we provide a device for locking the connection to the operator's position in question or to the impulse sender in question for further calls when a fault is perceived, in order that additional subscribers' calls are not endangered.

The invention is represented by way of example diagrammatically in the accompanying drawing, showing means by which in addition to the manipulations of the operator being controlled, *e. g.* preselectors, service selectors, group selectors, connectors, impulse senders and the like, which are worked with the exchange position, are brought

under the influence of the place of observation in order that when faults are perceived or suspected the said apparatus can be held or locked by suitable manipulations in the 5 normal connection of the system, so that the requisite determinations can be made with greater certainty in order to detect a defective apparatus or an operator who is not paying sufficient attention and adjust the 10 service selector to another keyboard when wrong impulses are sent.

Referring to the drawing, the arrangement shown comprises a calling station connected in known manner over a preselector 15 VW and a service selector DW to an exchange position. The inquiry line *a* is used at the same time as a line for transmitting the current impulses from the exchange position over the service selector DW to the 20 group selector GW and farther. The observation position is equipped with a switch S, to which branch lines lead from the line *a*. When throwing the switch S, which has four arms, into circuit at an exchange position 25 a receiver at the observation position is switched into circuit, over which the calls arriving at the exchange position can be heard. The switch S is common to a number of exchange positions, of which only one is 30 shown. In order to test the correctness of the current impulses issued by the exchange position, there is connected in series with the receiver a device, comprising a magnet which attracts its armature at each current 35 impulse and thereby produces a character on a movable band, which may be fed continuously or intermittently after each arriving call at a speed such that a sufficient space is obtained between the individual records of 40 the impulses in order to render them clearly perceptible.

When the observation position is connected into circuit the relay HR is energized over the key 1 and renders at the contact 45 *hr* the circuit for the relay T₁ independent of the impulse sender and thereby prevents the disconnection of the service selector and impulse sender. The contact I is opened 50 only temporarily by the impulse sender shortly before the termination of the impulses, and the contact II is closed during the impulses and closes the circuit for the relay T₂, so that the connection with the calling subscriber is interrupted. III designates the impulse contact at the *a*-branch 55 and IV the grounding contact at the *b*-branch. If wrong impulses are emitted the observing official will depress the key 2, to energize the relay U which holds itself and 60 can be released only by the key Tu. The relay U connects into circuit the locking magnet SpM which locks the key-board and thereby prevents wrong keys being depressed. The emission of impulses is 65 stopped at the contacts 3, 6' and control

lamps 5 and 6 are connected into circuit at the contact 4. The circuit of the relay T₁ is broken at the contact 7, the armature of this relay is released and connects into circuit the service selector which is connected to another keyboard. 70

If the correct impulses are emitted, the operator reverses the key 1 and thereby opens the circuit of the relay Hr. On its armature being released the circuit of the relay T₁ is 75 broken, for example by mechanical or electrical retardation means, until the armature of the relay T₁ can be released and switches the service selector in known manner into its rest position, or the keyboard is released, if 80 it is a service selector which remains in the position obtained on the establishment of the connection.

It will be obvious, that although only one embodiment of the invention is shown, many 85 modifications may be made without departing from the spirit of the invention, for instance for the Morse apparatus recording the impulses may be substituted any suitable means known in this art for rendering the 90 occurrences perceptible to the observing station.

We claim:

1. In a semi-automatic telephone system one or more observation stations, means at 95 said observation stations for supervising the talk between the operator at the exchange position and the calling subscriber, and means at said observation stations for supervising the impulse despatch by the operator of the exchange office without his knowledge. 100

2. In a semi-automatic telephone system one or more observation stations, means at 105 said observation stations for supervising the talk between the operator at the exchange position and the calling subscriber, means at said observation stations for connecting electrically said supervising means to the talking circuit of any one of the exchange 110 positions, means at said observation stations for recording the current impulses going from any one of the exchange positions to the selectors, and means for connecting the Morse apparatus to any one of said impulse 115 lines.

3. In a semi-automatic system one or more observation stations, means at said observation stations for supervising the talk between the operator at the exchange position 120 and the calling subscriber, means at said observation stations for connecting electrically said supervising means to the talking circuit, means at said observation positions for supervising the impulse despatch at the exchange office without the knowledge of the operator, and switching devices at said observation stations by means of which the apparatus which are in operative relation with the exchange are brought under the in- 125 130

fluence of the observing station for the purpose of any manipulations or determinations which may become necessary.

4. In a semi-automatic telephone system 5 one or more observation stations, a telephone apparatus at said observation stations, means at said observation stations for supervising the impulse despatch by the operator at the exchange position and switch- 10 ing devices under the influence of the observing station for connecting at will the telephone to the calling line or the supervising means to the impulse line for the purpose of sending and controlling feigned calls.
- 15 5. In a semi-automatic telephone system one or more observation stations, means at said observation stations for supervising the talk between the operator at the exchange position and the calling subscriber, means 20 at said observation stations for supervising the impulse despatch by the operator of the exchange position without his knowledge and means at the observation station for blocking the line to the exchange position 25 against further calls for the purpose of preventing an upsetting of the investigation and of further calls of subscribers by the faulty working of the apparatus.

6. In a semi-automatic telephone system one or more observation stations, means at 30 said observation stations for supervising the talk between the operator at the exchange position and the calling subscriber, means at 35 said observation stations for supervising the impulse despatch by the operator of the exchange position without his knowledge and means such as a change over switch at the observation station, which normally after finishing the despatch of impulses is separated from the established connection for 40 the establishment and maintenance of a listening circuit in order to overhear the conversation between the calling and called subscriber after the emission of impulses.

In testimony whereof we have set our 45 names in the presence of two witnesses.

- (1) GEORG GRABE.
- (2) FRITZ LUBBERGER.
- (3) GEORG FRÜBING.
- (4) HENDRICH BERTUS RÜTTER.

Witnesses as to signatures Nos. 1-3.

WOLDEMAR HAUPT,
HENRY HASPER.

Witnesses as to signature No. 4.

P. HILDERING,
C. KEITH.
